(57) **CLAIM**

The ornamental design for a U-shaped toilet lid as shown and described.

DESCRIPTION

FIG. 1 is a front, right, bottom perspective view of a U-shaped toilet lid showing my new design;

FIG. 2 is a front, right, top perspective view thereof;

FIG. 3 is a front view thereof;

FIG. 4 is a left view thereof;

FIG. 5 is a right view thereof;

FIG. 6 is a back view thereof;

FIG. 7 is an enlarged top view thereof;

FIG. 8 is an enlarged bottom view thereof;

FIG. 9 is an enlarged view of the encircled area 9 of FIG. 1;

FIG. 10 is an enlarged view of the encircled area 10 of FIG. 2;

FIG. 11 is an enlarged view of the encircled area 11 of FIG. 2;

FIG. 12 is an enlarged view of the encircled area 12 of FIG. 4;

FIG. 13 is an enlarged view of the encircled area 13 of FIG. 5;

FIG. 14 is an enlarged view of the encircled area 14 of FIG. 7; and,

FIG. 15 is an enlarged view of the encircled area 15 of FIG. 7.

The broken lines shown on the drawings depict portions of the U-shaped toilet lid that form no part of the claimed design.

1 Claim, 15 Drawing Sheets
